UNITED STATES PATENT OFFICE.

ROBERT H. BOLEN, OF NEW ORLEANS, LOUISIANA.

MOLD FOR FORMING SUNKEN CONCRETE STRUCTURES.

1,089,184.

Specification of Letters Patent.

Patented Mar. 3, 1914.

Application filed September 18, 1913. Serial No. 790,443.

To all whom it may concern:

Be it known that I, ROBERT HART BOLEN, citizen of the United States, residing at New Orleans, in the parish of Orleans and State of Louisiana, have invented new and useful Improvements in Molds for Forming Sunken Concrete Structures, of which the following is a specification.

The invention relates to the construction of concrete walls; and it has for one of its objects to simplify and cheapen the cost of construction of this type of wall.

Another object of the invention is to provide a novelly-constructed hollow pile, which can be driven into the ground, and which, when filled with concrete, may be readily withdrawn and again driven, filled with concrete, and withdrawn, the operation being repeated until the required length of wall has been constructed.

Still another object of the invention is to provide for the construction of circular and angular walls.

In the drawings—Figure 1 is a perspective view of my improved pile; Fig. 2, a transverse, longitudinal section of the same; Fig. 3, a horizontal, transverse section through the upper end of the pile and the driving-box; Fig. 4, a top plan view of a series of the piles interlocked together; Fig. 5, a perspective view of the driving-box; Fig. 6, a similar view of one of the hook-shape guides; Fig. 7, a horizontal section through the upper end, and driving-box of a modified form of pile; Fig. 8, a similar section through the lower end of the same, and Fig. 9 a plan view of a detachable bottom for the modified pile. Fig. 10 is a plan view of the bottom portion of the structure shown in Fig. 1.

Referring to the several views, the numerals 1 and 2 indicate channel-irons, preferably of steel, which form the respective sides of the pile. These two channel-irons are spaced apart any suitable or required distance, with their flanges extending outwardly, and are held apart by sleeves 3, 3, through which pass bolts 4 for securing the sides together. Situated at the top of the pile within the space between the two sides, is a driving-box 5, firmly bolted or riveted to the respective sides. This driving-box is very much shorter than the space length between the sides, so as to leave sufficient space at each side thereof for the entrance of the concrete. Each of the flanges at one

edge of the pile is provided with hook-shape guides 6, 6, which are firmly bolted or riveted to the flanges, and serve to guide an adjacent pile while being driven. For convenience of description, this edge of the pile will be hereinafter referred to as the "female" face, the opposite edge will be referred to as the "male" face. The inner corners of the flanges of the male face are provided with longitudinal dove-tail grooves 7, 7, and slidably-arranged in these grooves is a male protector-plate 8, provided at its upper end with a hole 9 in which a line or rope may be fastened to withdraw the plate when required. The lower end of the pile is provided with a bottom 10 hinged at one side as shown in Figs. 1 and 2, the opposite side being provided with short studs or projections 11, 11 which enter slots 12, 12 in the bottom, and serve to retain said bottom in position in starting the driving of the pile. The lower ends of the flanges are beveled or inclined to facilitate driving.

In the construction of a wall, using my improved pile, the first pile to be driven should be provided with male and female protector-plates, the latter plate 13, being slid into the guides 6, 6, and is left in place to form the end of the wall. The second pile with male protector-plates in place, as shown in Fig. 4, is then driven, the flanges of the male face being in the guides 6, 6. After the second pile has been driven, the male protector-plate is withdrawn from the first pile driven, leaving a clear space between the end female protector-plate 13 and the male protector-plate 8 in the second pile. After a suitable number of piles have been driven in this manner, a male protector-plate being in place in the last pile driven, all of the others—except the end female plate—being removed, the space between the two plates is filled with concrete. When the space is properly filled with the concrete, the first pile and the succeeding piles are then withdrawn, the spreader-bolts proving no serious obstruction, as they are easily passed through freshly-mixed concrete. On short piles, twenty feet and less in length, the spreader-bolts will not be required. The hinged bottom, as the pile is being pulled up, opens by the weight of the concrete bearing on it. Or the pile may be withdrawn, before filling with the concrete, a sufficient distance to allow the bottom to swing open by gravity.

It will be obvious that reinforcing rods or bars may be placed within the pile before concrete is poured in, if found necessary, as it often is in foundation work.

- 5 In driving the piles any suitable pile-driver may be used, and the ordinary lead-line running from the engine of the pile-driver over the leads can be used to pull up the piles when required.
- 10 For constructing circular walls, and turning corners at right angles, the pile used does not differ materially from the rectangular or straight-pile, except that the sides or channel irons are curved along their 15 longest dimensions, as shown at 14 and 15, Figs. 7 and 8, and when used in constructing a circular foundation or wall, four of these piles are driven in a circle, and after they are driven and the concrete poured 20 in, the piles are pulled up and the concrete allowed to set, after which the circle of earth forming the core can be removed, and if the foundation is to support a heavy structure the hole made by the removal of 25 the earth may also be filled with concrete. Instead of a hinged bottom, this form of pile is provided with a detachable plate bottom 16, which is provided with upturned lugs 17, which conform to the curvature of 30 the sides 14 and 15, and frictionally engage the same. When the pile is pulled up the plate remains in the ground.

Various changes in the detail of construction may be made without departing from 35 the spirit or scope of my invention, and therefore I do not limit myself to the exact construction herein described.

Having thus fully described my invention what I claim is—

- 40 1. A mold for forming concrete structures, comprising oppositely-disposed channel-irons having their flanges arranged outwardly, means for securing the irons apart from each other, guides formed on one set 45 of flanges, a detachable closure-plate slid-

able in said guides, and a detachable division-plate slidable in guide-ways, formed in adjacent edges of the other set of flanges.

2. A mold for forming concrete structures, comprising oppositely-disposed channel-irons arranged with their flanges extending outwardly, means for securing the irons a distance apart from each other, hook-shape guide-ways formed on one set of oppositely-disposed flanges, a detachable closure-plate 50 slidable in said guide ways, grooved guide-ways formed in the adjacent edges of the other set of flanges, and a detachable division-plate slidable in said guideways.

3. A mold for forming concrete structures, comprising oppositely-disposed channel irons having their flanges arranged outwardly, means for securing said irons spaced apart, hook-shape guide-ways formed on one set of flanges, a detachable closure plate 60 slidable in said guide-ways, grooved guide-ways formed in the adjacent edges of the other set of flanges, a detachable division-plate slidable in the grooved guideways, and a driving-Lox arranged between the channel-irons so as to leave a pouring-space at 70 each side thereof.

4. A mold for forming concrete structures, comprising oppositely-disposed channel-irons having their flanges arranged outwardly, means for securing the channel irons spaced apart, guide-ways formed on one set of flanges, a detachable closure-plate slid- 75 able in said guide-ways, grooved guideways formed in the adjacent edges of the other 80 flanges, a detachable division-plate slidable therein, and a hinged bottom arranged to open upon the withdrawal of the mold for a short distance.

In testimony whereof I affix my signature 85 in presence of two witnesses.

R. H. BOLEN.
